UNITED STATES PATENT OFFICE.

EUGENE ROBERTS, OF SALT LAKE CITY, UTAH, ASSIGNOR TO THE WESTERN STATES MACHINE COMPANY, OF SALT LAKE CITY, UTAH, A CORPORATION OF UTAH.

BACKING FOR CENTRIFUGAL BASKETS.

Application filed August 18, 1921. Serial No. 493,325.

This invention is intended to provide a construction which shall overcome certain difficulties in the use of centrifugal baskets of the type employed in sugar mills for extracting the liquid content from the sugar by centrifugal action.

These baskets are commonly made of cylindrical form with fairly coarse perforations in the cylindrical wall which is reenforced to withstand the internal pressure by means of circumferential iron ribs. To retain the solid particles of sugar, while allowing the liquid to escape, a finely perforated sheet metal screen is employed, and to afford communication between the fine perforations in the screen and the more wide perforations in the basket, a reticulated backing is interposed between the cylindrical basket wall and the interior perforated lining.

Heretofore it has been the practice to employ a long strip of wire netting of say $\frac{1}{4}$ inch mesh whose length is perhaps 4 or 5 inches greater than the internal circumference of the centrifugal basket for which it is intended, so that the two ends of the backing may overlap for a few inches. I have discovered in practice that the perforated linings or screens, when taken out of the basket, often show cracks or breaks extending vertically and upon investigation found that such cracks or creases in the screen are due to two causes, one of them being the unequal stretching of the bottom and top portions of the screen which leads to buckling, and the other cause being the result of the extra thickness formed by overlapping the ends of the backing which forms the intermediate support for supporting the screen against the outward thrust or pressure of the sugar mass.

The present invention overcomes this serious defect by providing a backing so constructed as to present no salient or jumping off place between the interior screen and the external basket wall capable of creasing or cutting the screen.

In the accompanying drawings I have illustrated a construction and arrangement embodying the principles of this invention in which:

Figure 1 is a perspective view showing the front half of the centrifugal basket cut away to expose the interior screen and a portion of the overlapped portion of the interior

backing on the outside of said screen, the screen perforations being omitted.

Figure 2 is a horizontal section through the overlapped front portion of the backing showing also a portion of the interior screen 60 on an enlarged scale, resting against the outer basket wall.

Figure 3 is an enlarged detail view showing the overlapped ends of the reticulated backing.

In the practice of this invention, according to the form illustrated in the drawings, a strip of wire netting of about $\frac{1}{4}$ inch mesh, more or less, of a height corresponding to the depth of the basket is cut off to a 70 length of approximately 4 or 5 inches greater than the interior circumference of the basket. This netting is usually of a plain in and out weave comprising longitudinal or circumferential wires 1, and vertical or transverse wires 2.

To prepare this backing for its long service I first remove entirely the two or three vertical strands or wires 2 adjacent to each end of the reticulated strip. After the removal of these vertical strands or wires there will be left circumferential or warp wires extending approximately $\frac{3}{4}$ of an inch, more or less, beyond the reticulated body portion of the strip. These circumferentially projecting ends are then ground off to taper the ends down to a point as indicated most clearly at 3 in Figure 2. The reticulated strip with its projecting end wires thus tapered or reduced is then folded 80 into a cylinder with overlapping ends and inserted inside the cylindrical wall 4 of the basket where it will be observed that the tapered ends lie snugly against the overlapped reticulated portion of the basket, the 85 tapered wires of the opposite ends of the backing being separated or extended some distance apart as best seen in Figure 2.

By this construction and arrangement I provide an ample overlap of the ends of the backing, while at the same time avoiding any crease producing projection or thickness liable to cause a break in the finely perforated lining or screen 5, and find in practice that the life of the screen as well as of the lining itself is very much prolonged, and that troubles due to unevenness in the interior surface of the screen heretofore caused by this overlap are fully prevented.

What I claim is:

1. In a centrifugal basket the combination with a perforated circumferential basket wall, an interior finely perforated screen, and an interposed reticulated backing comprising a strip of reticulated material where opposite end portions are overlapped with the circumferential strands projecting a substantial distance beyond the reticulated or woven body and gradually reduced in thickness radially to avoid the formation of creases in the screen when the screen is forced against the backing by the centrifugal pressure of the interior mass of material in the basket, substantially as described.
- 5 2. A backing for a centrifugal basket screen embracing an elongated strip of woven wire of a length somewhat greater than the interior circumference of its centrifugal basket to allow the ends to overlap when placed inside the basket, several of the transverse or vertical wires being removed from the extreme end portions of the strip to leave circumferentially projecting ends of wire, said projecting wire ends being tapered toward their tip ends to gradually reduce 25 their thickness radially, substantially as described.
- 10 3. A backing for a centrifugal basket comprising interwoven series of circumferential and vertical wires, the circumferential wires being of a length somewhat greater than the interior circumference of the basket to form an overlap and projecting a substantial distance beyond the vertical wires nearest their ends, said projecting end portions being tapered toward their tips to provide a gradually sloping incline to the overlapping portions of the woven body portion of the backing whereby the backing is enabled to support the outward thrust of 30 40 the screen without forming creases in the screen, substantially as described.
- 15 20

In witness whereof, I have subscribed the above specification.

EUGENE ROBERTS.
